Primary Examiner — Richard E Chilcot(74) Attorney, Agent, or Firm — McCarthy Tétrault LLPCLAIM

The ornamental design for sleeve cuff for a garment, as shown and described.

DESCRIPTION

FIG. 1 is a front view of a sleeve cuff for a garment according to the design;

FIG. 2 is an enlarged front view of the sleeve cuff of FIG. 1;

FIG. 3 is an enlarged rear view of the sleeve cuff of FIG. 2; FIG. 4 is an enlarged right side view of the sleeve cuff of FIG. 2;

FIG. 5 is an enlarged left side view of the sleeve cuff of FIG. 2;

FIG. 6 is an enlarged front perspective view of the sleeve cuff of FIG. 2;

FIG. 7 is an enlarged front view of the sleeve cuff of FIG. 2 shown in use with the slits in the sleeve cuff shown in their opened positions; and,

FIG. 8 is a rear view of the sleeve cuff for a garment of FIG. 1.

The portions shown in broken lines in FIGS. 1-8 do not form part of the claimed design. The broken line showing of the hand and wrist watch in FIG. 7 is for the purpose of illustrating portions of the environmental structure and forms no part of the claimed design.

1 Claim, 8 Drawing Sheets(56)
